(57) **CLAIM**

The ornamental design for a soldering station, as shown and described.

DESCRIPTION

FIG. 1 is a perspective view of a soldering station showing my new design;

FIG. 2 is a another perspective view thereof;

FIG. 3 is a front view thereof;

FIG. 4 is a back view thereof;

FIG. 5 is a left view thereof;

FIG. 6 is right view thereof;

FIG. 7 is top plan view thereof; and,

FIG. 8 is bottom plan view thereof.

The broken line showing of the soldering station is for the purpose of illustrating portions of the article and forms no part of the claimed design.

1 Claim, 8 Drawing Sheets
